UNITED STATES PATENT OFFICE.

GUGLIELMO MARCONI, OF LONDON, ENGLAND, ASSIGNOR TO MARCONI WIRELESS TELEGRAPH COMPANY OF AMERICA, OF NEW YORK, N. Y., A CORPORATION OF NEW JERSEY.

TRANSMITTING APPARATUS FOR USE IN WIRELESS TELEGRAPHY AND TELEPHONY.

1,136,477.

Specification of Letters Patent. Patented Apr. 20, 1915.

Application filed December 31, 1913. Serial No. 809,711.

To all whom it may concern:

Be it known that I, GUGLIELMO MARCONI, a subject of the King of Italy, residing at Marconi House, Strand, London, England, have invented new and useful Improvements 5 in Transmitting Apparatus for Use in Wireless Telegraphy and Telephony, of which the following is a specification.

This invention relates to improvements in 10 transmitting apparatus for use in wireless telegraphy and telephony whereby continuous oscillations or groups of continuous oscillations may be generated.

The accompanying drawings illustrate my 15 invention, Figure 1 being a diagrammatic representation of a transmitter constructed in accordance therewith while Fig. 2 is a similar representation of a modified form.

k k' is a split condenser which can be 20 charged by a source of current a which is preferably continuous through an inductive resistance i , a key b being included in the circuit. From the middle of the condenser k k' a plurality of condensers c' c^2 c^3 is 25 connected each through an inductive resistance i' i^2 i^3 to pairs of terminals t' t' , t^2 t^2 , t^3 t^3 . The outer plates of the condenser k k' are connected one to each of a pair of toothed disks d d' fast on the same rapidly 30 rotating shaft e . The teeth on the two disks and the terminals t' t' , t^2 t^2 , t^3 t^3 are so arranged that as the teeth pass the terminals the condensers c' c^2 c^3 are charged in the 35 same direction and then discharged in succession and then charged in the opposite direction and discharged in succession.

s' s^2 s^3 are portions of a winding which act as secondaries to the primaries i' i^2 i^3 and which is included in an oscillating circuit o 40 inductively coupled to an aerial f .

g g' are air blasts for quenching the discharge at the terminals t' t' , t^2 t^2 , t^3 t^3 .

The speed of the toothed disks should obviously be such that the aerial receives 45 impulses in synchronism with its natural time period.

In the modification shown in Fig. 2 instead of having three inductive resistances connected one to each of the condensers 50 c' c^2 c^3 , two inductive resistances i' i^2 are employed between the condenser k k' and the disks d d' and these resistances act as primaries to secondaries s' s^2 in the oscillating circuit o . In this case the interval

between successive discharges is equal to or 55 a multiple of the natural time period of the aerial.

All the circuits c' i' k d , c' i k' d' , c^2 i^2 k d , c^2 i^2 k' d' should be in resonance with the circuit o and with 60 the aerial. Similarly the circuits c' k i' d , c' k' i^2 d' , c^2 k i' d , c^2 k' i^2 d' should be in resonance with the circuit o and with the aerial.

I may employ a larger odd number of 65 working condensers the primaries being wound alternately in opposite directions so that the aerial is impelled in opposite directions alternately or otherwise in synchronism with its natural period of electrical 70 oscillation the spacing of the teeth and the speed of rotation of the disks being suitably arranged. The primaries may however be all wound the same way, the aerial being impelled once every complete period of oscillation or otherwise in synchronism with its 75 natural period, in which case I am not limited to employing an odd number of working condensers.

One half of the split condenser may be 80 short-circuited and if the inductance of the generator be sufficiently low, the other half omitted.

What I claim is:—

1. The combination of a plurality of condensers in parallel, and means for charging them with electricity in opposite directions alternately and for discharging them in regular succession through inductive resistances substantially as described. 85

2. The combination of a plurality of condensers in parallel, means for charging them with electricity and a rotating disk adapted to discharge the condensers in succession through inductive resistances and a second 95 rotating disk adapted to discharge the condensers in succession after the first disk has done so.

3. The combination of a plurality of condensers in parallel, means for charging them 100 with electricity in opposite directions alternately, a plurality of inductive resistances, means for discharging the condensers in regular succession through the resistances and a winding having portions adapted to 105 act as secondaries to the primaries formed by the resistances.

4. The combination of a plurality of con-

- condensers in parallel, means for charging them with electricity in opposite directions alternately, a plurality of inductive resistances, means for discharging the condensers in regular succession through the resistances and an oscillating circuit having portions adapted to act as secondaries to the primaries formed by the resistances, formed by the resistances, and an aerial inductively coupled to this circuit.
10. 5. The combination of a plurality of condensers in parallel; an inductive resistance connected to each condenser, a winding having portions adapted to act as secondaries to the primaries formed by the inductive resistances, and means for charging the condensers with electricity in opposite directions alternately and for discharging them in regular succession.
15. 6. The combination of a plurality of condensers in parallel, an inductive resistance

connected to each condenser, an oscillating circuit having portions adapted to act as secondaries to the primaries formed by the inductive resistances, means for charging the condensers with electricity in opposite directions alternately and for discharging them in regular succession, and an aerial inductively coupled to the oscillating circuit.

7. The combination of a plurality of condensers in parallel and means comprising 30 rotating spark gaps for charging them with electricity in opposite directions alternately and for discharging them in regular succession through inductive resistance, substantially as described.
